UNITED STATES PATENT OFFICE.

ALVAH RICE, OF ROCHESTER, NEW YORK, ASSIGNOR OF ONE-HALF TO
STEPHEN WHEELER, OF SAME PLACE.

CAR-COUPING.

SPECIFICATION forming part of Letters Patent No. 256,859, dated April 25, 1882.

Application filed February 6, 1882. (No model.)

To all whom it may concern:

Be it known that I, ALVAH RICE, of Rochester, in the county of Monroe and State of New York, have invented a new and useful 5 Improvement in Car-Couplers, which improvement is fully set forth in the following specification and accompanying drawings.

The object of my invention is to attach a retaining-gate at the side of the bumper-head of 10 an ordinary draw-bar of a railroad-car for the purpose of holding in position the coupling-link or the coupling-pin, as the case may be, during the process of coupling two cars together, with certain other attached and 15 combined parts, all of which are fully described in the subjoined specification, and more particularly pointed out in the claims.

Referring to the accompanying drawings, 20 Figure 1 is a plan or top view of my improved coupling device; Fig. 2, a side elevation of the same, view indicated by arrow *y* in Fig. 1; and Fig. 3, a view of a section of the link and a portion of the outer free end of the gate in position to hold the link, view indicated by arrow 25 *z* in Fig. 1.

A is the bumper-head, having the usual opening, F B the bumper-ring or bumper, G the hole for the pin, D the pin, and C the coupling-link, all of ordinary construction, 30 which parts together constitute the external or visible portion of the car-coupling device in general use.

In using this style of coupler it is necessary for an attendant to stand at the end of the car 35 to be connected and guide the link of the approaching car into the opening of the bumper-head of the said car to be connected, and place the pin of said bumper-head through said link when in position—an operation that is at once 40 troublesome and dangerous, and which by the use of my improvement is avoided.

To the back surface, and at one side of the bumper-ring B of the ordinary coupling device above described, I attach a simple gate, *b*, constructed to swing horizontally into or out of the opening F of the bumper, the said gate swinging upon a vertical pin, *a*, held by two projecting hangers, *c c*, as shown. The upper edge or surface of the gate is plain, but the

lower edge is notched at *d*, to allow said gate 50 to swing over the link C' within the head, (shown in dotted lines,) and also notched at *e* over the hanger *c*, to allow it to drop a short distance vertically when swung out of the opening F of the head. The gate, when swung 55 to its farthest position within the head, as shown in full lines in the figures, stands in line with the hole G for the pin, and forms a rest for the pin, as shown, to hold the same up out of the way of the approaching link *c* of an 60 other car. When the link C enters the bumper-head it swings the gate around to the position indicated in dotted lines at *b*² and allows the pin to drop through said link and perfect the coupling of the two cars. 65

A projecting part, *f*, from the side of the gate, and coming in contact with the bumper-ring B when the gate is swung within the head, forms a stop to prevent said gate swinging beyond or by the hole G. 70

If the operation of coupling is to be reversed—that is to say, if the link and pin are both in place in the head herewith shown and approaching another car with which to be coupled—then the gate is to be swung to the position 75 shown at *b*² in dotted lines against the pin D, and over the end of the link C', as appears in Fig. 1, which is sufficient to hold the link temporarily in position for the purpose of coupling. The lower inside corner of the gate is 80 rounded back, as shown at *s* in Fig. 3, which, together with the convexity of the link, causes the gate to be thrown off or to slide off the link by the jar or concussion caused by the bumpers striking together, and also the backward 85 motion of the link incident to coupling tends to swing the gate around off the link.

A piece, *g*, projects laterally from the side of the head under the gate, out upon which the downward projecting part *o* of said gate rides 90 when the latter is swung outward to the position shown in dotted lines at *b*². The upper surface of the piece *g* inclines downward away from the head, so as to facilitate the swinging outward of the gate, and when the latter has 95 reached the position shown at *b*², or when the part *o* of the gate moves wholly off the ledge *g*, the gate is permitted to drop vertically a

short distance on account of the same being cut away at ¹⁵ cover the lower hanger *c*, as above stated. When the gate has dropped to its lowest position its rests upon the lower hanger *c*, and the part *o* passes a little distance below the outer upper corner of the ledge *g*, which prevents the gate swinging forward into the head when not needed. The outer projecting corner, *p*, of the gate, coming in contact with the bumper-ring *B* when said gate is swung outward, forms a stop to prevent the same swinging farther back than to the position shown at *b*².

The gate has to be raised and swung into the head by hand when it is needed to hold either the pin or link. I do not claim the holding of the pin of a car-coupler up out of the way of the approaching coupling link of another car, nor holding the link in position to enter the bumper of an approaching driving car, such having before been accomplished; but

What I claim as my invention, and wish to secure by Letters Patent, is—

1. The open bumper-head *A* of a car-coupling device, provided with a projecting bumper-ring, *B*, and a gate, *b*, hung to said bumper-ring at the rear side thereof, and in such a manner that it may be swung into the opening *F* of the bumper-head, substantially as and for the purpose set forth.

2. The open bumper-head *A* of a car-coupling device, provided with a projecting bumper-

ring, *B*, and a gate, *b*, hung at the rear side of said bumper-ring, and in such a manner that it may be swung into the opening *F* of the bumper-head, as set forth, said gate when swung within the bumper-head being adapted to the double purpose of holding in position either the coupling-link or coupling-pin, as may be required.

3. In combination with the bumper-head *A*, having an opening, *F*, a link, *C*, and pin *D*, a gate, *b*, hung at one side of the head and so as to be swung into or out of the opening *F*, and capable of being moved vertically up or down upon its bearing or hinge, substantially as described, and for the purpose set forth.

4. In a car-coupling device, the gate *b*, provided with the downward-projecting part *o*, and hung to the rear side of the bumper-ring *B*, so as to be swung into the opening *F* of the bumper-head, said bumper-head being provided with the ledge *g*, projecting laterally from the lower plate thereof, and in position for the said part *o* of the gate to ride upon while the latter is being swung, as and for the purpose set forth, the said ledge *g* also forming, with the part *o*, a stop for the gate when the latter is swung out of the bumper-head to prevent it being swung therein again until needed.

ALVAH RICE.
